J. W. Brooks
Corset.

No. 99,140.

Patented Jan. 25, 1870

Witnesses.

John W. Brooks
Hugh McCormick

Inventor

J. W. Brooks
By atty A. B. Strongton

United States Patent Office.

J. W. BROOKS, OF BOSTON, MASSACHUSETTS.

Letters Patent No. 99,146, dated January 25, 1870.

IMPROVEMENT IN CORSET SKIRT-SUPPORTERS.

The Schedule referred to in these Letters Patent and making part of the same

To all whom it may concern:

Be it known that I, J. W. BROOKS, of Boston, in the county of Suffolk, in the Commonwealth of Massachusetts, have invented a new and useful Improvement in Corset Skirt-Supporters; and I do hereby declare that the following is a full and exact description thereof, reference being had to the accompanying drawings, and to the letters of reference marked thereon, and making a part of this specification, and of which—

Figure 1 represents a view of an ordinary corset, with the supporter attached thereto.

Figure 2 represents a section through the corset and supporter, taken at the red line x x of fig. 1; and

Figure 3 represents a similar section, taken at the red line y y of fig. 1.

Figure 4 represents an extension-piece or flap, which is secured to the corset, but which can be removed therefrom when desired, and in or by which the stiffener is in part or in whole supported.

Figure 5 represents a horizontal section through the corset, and showing the stiffener in position.

Similar letters of reference, where they occur in the several separate figures, denote like parts in all of the drawings.

My invention consists, first, in combining with a corset a skirt-supporter, having one or more adjustable extension-straps, or other known adjusting-device, by which it may be raised or lowered, or allowed to project more or less from the person of the wearer, as may be desired.

And my invention further consists in combining, with the stiffener of a corset skirt-supporter, hooks, straps, or other readily-adjusted fastening and unfastening-devices, by which said stiffener may be regulated in or on the supporter.

To enable others skilled in the art to make and use my invention, I will proceed to describe the same, with reference to the drawings.

A represents a corset, of any of the usual well-known forms of construction or of material; and

B represents the skirt-supporter in question, attached thereto, but so that it may be detached therefrom when desired, and worn, or not, with the corset, at pleasure.

C is a stiffener, of rattan or any other material used for such purpose, and may be secured to the supporter by being inserted in a pocket, a, therein, or by straps, b b, having hooks, c, and eyelet-holes, 1, 2, 3, &c., connected with them, by which said stiffener may be held and adjusted, or by both pocket and straps, as may be preferred, and the supporter and straps, which may be termed, also, the stiffener-holders, may be united to the corset by hooks and eyelets, straps and buckles, tapes, or by temporary stitching, or other well-known attaching and readily-releasing mechanism or device.

In fig. 5, one end of the supporter, viz., that to the left of said figure, is represented as united to the corset by means of a hook, d, taking into one of a series of adjusting-holes (or eyelets) 4, 5, 6, &c., in the corset, but which may be on a separate piece of leather or cloth, and attached to the corset in a more or less temporary manner.

The other end of the supporter, viz., that to the right of fig. 5, is secured to the corset by slipping into a pocket, e, on or in the corset, but without uniting it immovably in said pocket.

To that end of the stiffener in the pocket e, there is secured a strap, f, which extends rearward, and by any one of its series of holes is united to a buckle, g, that is fastened to or on the corset A, so that this end of the stiffener, though in the pocket e, may, by its strap and buckle, be extended or projected from the person of the wearer, more or less, as may be required.

I mention the buckle and strap as the adjusting-mechanism, because I prefer its use, but tapes, hooks and eyes, and straps may be substituted therefor, without changing the character of the invention; and in describing and representing any special kind of adjustable fastening, I mention that kind which I find answers a good purpose, but do not limit myself to that kind specially, meaning to use any of the common known kinds.

The pocket a need not extend entirely around the supporter B, but may terminate at h, and the portion beyond h, and between it and the end i may be a flap only, so as to cover or drop over the end of the stiffener and its hook d.

The buckle g, instead of being fastened to the corset where shown, may be put further around, or even on the front of the corset, and the strap f extend to it there, where it might be more accessible for adjustment, or it may be on the stiffener, and the strap on the corset; but these changes are so obvious, that it is scarcely worth while to recite them, and would in no wise change the characteristics of the invention.

From the description, it will be seen that this supporter can be attached to any and all descriptions of corsets, and that by the use of the adjustable extension-straps, and the means devised for moving the ends of the stiffeners back and forth, the supporter can be raised and lowered, or can be projected or extended outward from the person of the user, to a greater or less distance, at the pleasure of the wearer.

Both ends of the stiffener may be adjusted and held by similar devices, instead of different ones, and by putting the strap on one end, and the buckle on the other end, the two ends may be simultaneously moved or adjusted.

Having thus fully described my invention, What I claim therein as new, and desire to secure by Letters Patent, is—

The combination, with a corset, of a skirt-supporter, having one or more adjustable extension-straps, b f, by which it may be raised or lowered, or extended or projected more or less from the person of the wearer, substantially as and for the purpose described.

Also, in combination with the stiffener of a corset skirt-supporter, the hooks and eyelets, or strap and buckle, or other similar adjustable fastening-devices, for moving and holding said stiffener further from or nearer to the person of the user or wearer, substantially as and for the purpose described.

J. W. BROOKS.

Witnesses:

W. D. BROOKS,
J. B. THAYER.